UNITED STATES PATENT OFFICE.

CHARLES H. SCHURR, OF CLEVELAND, OHIO, ASSIGNOR TO THE LEES-BRADNER COMPANY, OF CLEVELAND, OHIO, A CORPORATION OF OHIO.

TESTING APPARATUS.

Application filed August 26, 1922. Serial No. 584,510.

This invention relates to an apparatus for testing gears to determine the accuracy or inaccuracy of the spacing of the gear teeth thereof.

5 One object of the invention is to provide an apparatus of this character of relatively simple construction capable of indicating inaccuracies in the spacing of the gear teeth.

Another object of the invention is to provide 10 an improved apparatus of this character in which means are provided for measuring or comparing the spacing between the teeth of a gear to determine the accuracy or inaccuracy thereof.

15 Other objects of the invention will be apparent to those skilled in the art to which my invention relates from the following description, taken in connection with the accompanying drawing, wherein

20 Fig. 1 is a top plan view of an apparatus embodying my invention.

Fig. 2 is a section on the line 2—2 of Fig. 1.

25 Fig. 3 is a section on the line 3—3 of Fig. 1.

Referring to the drawing, 1 indicates a base or bed of any desired construction, but preferably supported on a plurality of legs 2. The top 1^a of the base or bed 1 is preferably disposed horizontally. The top 1^a 30 consists of a plane to permit movement of a frame 4 thereon if the latter is rotated about the axis of a shaft 5, but in the preferred arrangement, the frame 4 is held stationary and the gear A is indexed or moved in the manner to be later set forth. The frame 4 comprises an outer member formed of a pair of bars 4^a connected together at their opposite ends and held in 35 spaced parallel relationship by links 4^b, and an inner or intermediate member 4^c disposed between the bars 4^a. The intermediate member 4^c is formed with an opening 4^d to receive a supporting member for a gear A, 40 preferably comprising a spindle or shaft 5. The inner side edges of the bars 4^a and outer side edges of the member 4^c are shaped to form inter-engaging guide surfaces, whereby the outer member may be moved or adjusted relative to the inner member 4^c radially of the shaft 5 by means indicated as an 45 entirety at 6. Of these moving means, 6^a indicates a rod extending through and having bearing in an opening 6^b formed in one of the links 4^b. The inner end of the rod is

screw threaded and engages a nut 6^c fixed in an opening 6^d formed in the member 4^c (see Fig. 2). The rod 6^a is held against endwise movement outwardly by a collar 7, which engages the inner face of the adjacent link 4^b; to control its movement inwardly, I provide between the link 4^b and a shoulder 7^c (the shoulder preferably comprising a head by which the rod 6^a is rotated) a spring 7^a; the collar 7 and spring 7^a through their engagement with the adjacent link 4^b serving to insure movement of the bars 4^a relative to the intermediate member 4^c when the rod 6^a is rotated in one direction or the other.

The base or bed 1 is formed with an opening 8, surrounding which is a depending member 9, preferably of tubular shape, adapted to receive a bushing 10, the latter being provided with a collar 11, which engages the top 1^a and supports the bushing 75 in the tubular member 9. The tubular member 9, as well as the strengthening ribs 12 and lugs 13 (to which the legs 2 are secured) are preferably formed integrally.

The shaft or spindle 5 removably fits the bushing 10, being provided with a ring 14 which engages a washer 15, disposed on the upper end of the bushing 10, to support the shaft or spindle 5 in position. As shown in Fig. 2, the washer 15 extends over the intermediate frame member 4^c to engage its upper surface so as to hold the intermediate frame member, and through it the bars 4^a, in engagement with the top 1^a. At its lower end, the shaft or spindle 5 may be reduced, as 80 shown at 16 and such reduced end is provided with screw threads to receive a nut 17, which may be tightened against a washer 19. As the washer 19 engages the lower end of the bushing 10, it will be seen that the 85 nut 17, when tightened, serves to prevent endwise, and, by preference, rotary movement of the shaft or spindle 5. At its upper end the supporting member or spindle 5 is shaped to engage and support a gear, the 90 teeth of which are to be tested; where the gear is provided with a bore or shaft opening, as shown in the drawings, the support or spindle 5 is reduced to provide an arbor or support 20 for the gear A. In practice, it 95 is customary to position the gear on the arbor 20, as will later be set forth, to test the spacing of two adjacent teeth and to then raise the gear or remove it from the arbor 100 and turn it an angular distance equal to the 105 110

spacing of one or more teeth, and then re-position it on the arbor in testing position, but if desired, in making each test, the gear A may be removably held on and fixed 5 to the arbor 20 by a nut 21 engaging screw threads provided on that portion of the shaft or spindle 5 which extends beyond the arbor 20.

23, 23, indicate a pair of abutments carried 10 by the frame 4, each abutment being mounted on one of the bars 4^a the abutments 23 are arranged equal distances from one end of the frame and at opposite sides of a plane containing the axis of the gear A or the shaft 15 5. Each abutment 23 preferably comprises a roller 23^a mounted on a shaft 23^b fixed in an opening 23^c formed in the adjacent bar 4^a. I preferably provide on the shaft 23^b an anti-friction bearing the outer race of which 20 may serve as the roller 23^a.

24 indicates an annulus fixed to the shaft 5, preferably corresponding in diameter to one of the circles of the gear A, for example, the base circle thereof. The annulus 24 may 25 be connected to the shaft 5 in a manner which permits its removal, when desired. As will later appear, the annulus 24 forms an abutment element for a support indicated as an entirety at 25.

30 The support 25 extends transversely of the frame 4 and has a central rearwardly extended portion 25^a and a depending flange 26 along its front edge. The flange is disposed between the abutments 23 and the annulus 24, 35 the abutments being operated by the moving means 6 to yieldingly hold the flange against the annulus and to thereby maintain the support 25 in the position shown in Figs. 1, 2 and 3. When it is desired to remove the support 25, the rod 6^a is operated to move the abutments away from the shaft 5. From the foregoing description it will be seen that I provide circular shaped elements 5, 9, 10 and 24, this construction facilitating their assembly without regard to any predetermined angular relation to each other or of the abutment element (annulus 24) for the support 25 relative to the latter or the abutments 23.

27, 28, indicate devices for engaging the 50 corresponding working faces of adjoining teeth *a* of the gear A to determine whether the spacing thereof is correct or not. The device 27 is preferably connected to a plate 29 which is adjustably carried by a base 30, whereby it may be fixed in any predetermined position for operative relationship 55 with the tooth engaging device 28. The base 30 is formed with a groove 31 to slidably receive the plate 29 and also a plurality of 60 openings 32 which (or one thereof, as shown) may receive a set screw 33 that clamps the plate in its adjusted position. As shown, the groove 31 is extended from end to end of the base 30 and the latter is formed with 65 openings 32' at the opposite side of a line

extending radially of the shaft 5, whereby the tooth engaging devices may be positioned to engage the opposite faces of the gear teeth *a* from those shown in the drawings. The tooth engaging device 28 comprises a lever fulcrumed at 34, whereby it may be moved due to inaccuracy occurring in the spacing of any two gear teeth *a*, and thus cause an indicating or measuring mechanism, indicated as an entirety at 35, to show the amount of inaccuracy existing. The indicating or measuring mechanism may be of any suitable construction, that shown comprising a casing 36 having a laterally extending tubular arm or sleeve 37 removably clamped between a pair of standards 38, having a shank detachably mounted at its lower end in an opening formed in the base 30. 39 indicates a plunger the outer end of which is engaged by the tail 28^a of the lever which forms part of the tooth engaging device 28 and adapted to be actuated thereby. The plunger 39 extends through the arm or sleeve 37 and is operatively connected at its inner end with a hand 40 which is mounted on the casing 36 and associated with a dial 41 to show the displacement of the device 28 due to the inaccuracy occurring in the gear teeth spacing. The tail 28^a is preferably supported on a pedestal 42, its movement in either direction being limited by upstanding pins 43. When the tooth engaging devices 27, 28, are to be positioned to test the opposite faces of the teeth from those shown in the drawings, the shank for the standards 38 may be positioned in an opening 44 so as to support the indicating or measuring mechanism 35 in corresponding relationship to the tail 28^a. The lever 28 is removably positioned on its fulcrum 34 by a knurled sleeve 45.

At 46, the support 25 is formed with a guideway, preferably extending radially of the shaft 5, and at 47, the lower face of the base 30 is provided with a guide or rib slidably fitting the guideway 46, thereby permitting guided movement of the base 30 toward and from the shaft 5 to position the tooth engaging devices 27, 28, for contact or engagement with the teeth of gears of different diameters; suitable means being provided for clamping the base 30 in its adjusted position. The clamping means just referred to preferably comprise one or more screws 48, each extending through an elongated opening formed in the base 30 and fitting a screw threaded opening 30^a formed in the support 25 and arranged to clamp the base thereto when the screw is tightened. I prefer to provide two such clamping means as shown in the drawings.

From the foregoing description it will be apparent that, since the contact devices 27 and 28 are both mounted on the base 30 and the latter is secured to the support 25, which carries the flange 26; and since the flange

26 is in contact with and tangent to the annulus 24 coaxial with the gear A to be tested, it follows that the free ends of the contact devices 27 and 28 will each contact with its corresponding tooth face at a fixed predetermined distance from the axis of the gear.

Fig. 1 shows the operation of testing the spacing of two adjoining gear teeth, the hand 40 pointing to zero on the dial 41 and thereby indicating that the spacing of these teeth is correct. By raising the gear A out of engagement with the contact devices 27, 28, the gear A may be rotated or indexed and then positioned so that the devices 27, 28, will engage the corresponding working faces of the next teeth, respectively. This operation may be repeated until all of the teeth have been tested. While I prefer to rotate or index the gear an angular distance sufficient to move the next tooth into operative relation to the devices 27, 28, the gear may be rotated a greater distance for each testing operation. Where the gear is clamped in position by the nut 21 for making a test (as shown in Fig. 2), it is first loosened or removed to permit indexing in the manner just described. If desired the gear may be reversed or the devices 27, 28, and indicating mechanism 35 may be positioned to test the opposite faces of the gear teeth a.

While in the disclosure herein I provide for the removal of the gear and its indexing relative to the shaft 5, I may in some instances secure the gear A to the shaft 5 and move it first substantially endwise and then about its axis, and in other instances other forms of shaft 5 itself which will occur to those skilled in this art may be employed.

From the foregoing description it will be seen that my construction is relatively simple and easily operated. In practice I have found that very slight inaccuracies in the gear pitch may be readily indicated and measured by the apparatus herein disclosed.

To those skilled in the art to which my invention relates many modifications and widely differing embodiments and applications of the invention will suggest themselves. It will be understood that the illustrations and disclosures herein are purely illustrative and not intended to be in any sense limiting.

What I claim is:

1. In apparatus of the class described, the combination of a support for a gear, a supporting means disposed in the plane of the gear on said support, a pair of devices removably mounted on said supporting means and arranged simultaneously to engage corresponding faces of adjoining teeth of the gear, one of said devices being normally fixed and the other device being movable, one of said devices being adjustable on said supporting means toward and from the other device, an indicator operatively connected

with said movable device, and means for adjusting said supporting means toward and from said support.

2. In a gear testing apparatus for testing the spacing of the successive teeth of a gear, a support for a gear to be tested, two measuring elements positioned relatively to the gear support so as to engage respectively two homologous faces of adjacent teeth of a gear on the support, the point of engagement of each element and tooth being at a predetermined fixed distance from the rotational axis of the gear, and indicating means associated with said elements for indicating the distance between the points of engagement. 80

3. In a gear testing apparatus for testing the spacing of the successive teeth of a gear, a support for a gear to be tested, two measuring elements positioned relatively to the gear support so as to engage respectively two homologous faces of adjacent teeth of a gear on the support, the point of engagement of each element and tooth being at a predetermined fixed distance from the rotational axis of the gear, one of said elements being movable, and indicating means associated with said movable element for indicating the distance between the points of engagement. 85

4. In a gear testing apparatus for testing the spacing of the successive teeth of a gear, a support for a gear to be tested, two measuring elements positioned relatively to the gear support so as to engage respectively two homologous faces of adjacent teeth of a gear on the support, the point of engagement of each element and tooth being at a predetermined fixed distance from the rotational axis of the gear, one of said elements being fixed and the other movable relatively thereto, and indicating means associated with said movable element for indicating the distance between the points of engagement. 100

5. In a gear testing apparatus for testing the spacing of the successive teeth of a gear, a frame, a support on the frame for supporting a gear to be tested with its rotational axis stationary but with the gear movable rotatively about the axis and movable longitudinally along the axis, two measuring elements mounted on the frame, spaced apart and positioned relatively to the support so that, in testing the spacing of successive teeth of the gear, the gear on the support may be rotated to bring a tooth of the gear 120 opposite the space between the measuring elements, moved axially to bring the tooth between the two elements, rotated to cause the elements to engage respectively two homologous faces of adjacent gear teeth and 125 moved axially from said engagement for similarly engaging succeeding teeth of the gear, and indicating means associated with said elements for indicating the distance between the points of engagement. 130

6. In a gear testing apparatus for testing the spacing of the successive teeth of a gear, a frame, a support on the frame for supporting a gear to be tested with its rotational axis stationary but with the gear movable rotatively about the axis and movable longitudinally along the axis, two measuring elements mounted on the frame, spaced apart and positioned relatively to the support so that, in testing the spacing of successive teeth of the gear, the gear on the support may be rotated to bring a tooth of the gear opposite the space between the measuring elements, moved axially to bring the tooth between the two elements, rotated to cause the elements to engage respectively two homologous faces of adjacent gear teeth and moved axially from said engagement for similarly engaging succeeding teeth of the gear, one of said elements being movable, and indicating means associated with said movable element for indicating the distance between the points of engagement.
7. In a gear testing apparatus for testing the spacing of the successive teeth of a gear, a frame, a support on the frame for supporting a gear to be tested with its rotational axis stationary but with the gear movable rotatively about the axis and movable longitudinally along the axis, two measuring elements, one of which is fixed and the other of which is movable relatively thereto, mounted on the frame, spaced apart and positioned relatively to the support so that, in testing the spacing of successive teeth of the gear, the gear on the support may be rotated to bring a tooth of the gear opposite the space between the measuring elements, moved axially to bring the tooth between the two elements, rotated to cause the tooth to engage the fixed element as a stop and to cause the two elements to engage respectively two homologous faces of adjacent gear teeth and be moved axially from said engagement for similarly engaging succeeding teeth of the gear, and indicating means associated with said movable element for indicating the distance between the points of engagement.
8. In a gear testing apparatus for testing the spacing of the successive teeth of a gear, a frame, a support on the frame for supporting a gear to be tested with its rotational axis stationary but with the gear movable rotatively about the axis and movable longitudinally along the axis, two measuring elements, one of which is fixed and the other of which is movable relatively thereto, mounted on the frame, spaced apart and positioned relatively to the support so that, in testing the spacing of successive teeth of the gear, the gear on the support may be rotated to bring a tooth of the gear opposite the space between the measuring elements, moved axially to bring the tooth between the two elements, rotated to cause the tooth to engage the fixed element as a stop and to cause the two elements to engage respectively two homologous faces of adjacent gear teeth, and indicating means associated with said movable element for indicating the distance between the points of engagement.

to engage the fixed element as a stop and to cause the two elements to engage respectively two homologous faces of adjacent gear teeth and be moved axially from said engagement for similarly engaging succeeding teeth of the gear, the point of engagement of each element and tooth being at a predetermined fixed distance from the rotational axis of the gear, and indicating means associated with said movable element for indicating the distance between the points of engagement.

9. In a gear testing apparatus for testing the spacing of the successive teeth of a gear, a frame, a support on the frame for supporting the gear to be tested, with its rotational axis stationary but with the gear movable rotatively about the axis, two measuring elements mounted on the frame and positioned relatively to the support so that the gear, when mounted on the support with a tooth thereof between the two elements, may be rotated to cause the elements to engage respectively two homologous faces of adjacent teeth of the gear, and indicating means associated with said elements for indicating the distance between the points of engagement.

10. In a gear testing apparatus for testing the spacing of the successive teeth of a gear, a frame, a support on the frame for supporting the gear to be tested, with its rotational axis stationary but with the gear movable rotatively about the axis, two measuring elements mounted on the frame and positioned relatively to the support so that the gear, when mounted on the support with a tooth thereof between the two elements, may be rotated to cause the elements to engage respectively two homologous faces of adjacent teeth of the gear, one of said elements being movable, and indicating means associated with said movable element for indicating the distance between the points of engagement.

11. In a gear testing apparatus for testing the spacing of the successive teeth of a gear, a frame, a support on the frame for supporting the gear to be tested, with its rotational axis stationary but with the gear movable rotatively about the axis, two measuring elements, one of which is fixed and the other of which is movable relatively thereto, mounted on the frame and positioned relatively to the support so that the gear, when mounted on the support with a tooth thereof between the two elements, may be rotated to cause the tooth to engage the fixed element as a stop and to cause the two elements to engage respectively two homologous faces of adjacent gear teeth, and indicating means associated with said movable element for indicating the distance between the points of engagement.

In testimony whereof, I have hereunto signed my name.

CHARLES H. SCHURR.
